CLAIM

The ornamental design for an electric switch, as shown and described.

DESCRIPTION

FIG. 1 is a perspective side view of an embodiment of an electric switch.

FIG. 2 is a front side view of the electric switch shown in FIG. 1.

FIG. 3 is a rear side view of the electric switch shown in FIG. 1.

FIG. 4 is a right side view of the electric switch shown in FIG. 1.

FIG. 5 is a left side view of the electric switch shown in FIG. 1.

FIG. 6 is a top side view of the electric switch shown in FIG. 1.

FIG. 7 is a bottom side view of the electric switch shown in FIG. 1; and,

FIG. 8 is another side perspective view of the electric switch shown in FIG. 1.

In the drawings, the broken lines depict portions of the switch which form no part of the claim.
